UNITED STATES PATENT OFFICE.

WILLIAM E. ALLEN, OF SALEM, MASSACHUSETTS, ASSIGNOR TO THE DRAPER COMPANY, OF PORTLAND, MAINE, AND HOPEDALE, MASSACHUSETTS.

WARP STOP-MOTION FOR LOOMS.

SPECIFICATION forming part of Letters Patent No. 608,971, dated August 9, 1898.

Application filed November 23, 1897. Serial No. 659,621. (No model.)

To all whom it may concern:

Be it known that I, WILLIAM E. ALLEN, of Salem, county of Essex, State of Massachusetts, have invented an Improvement in Warp Stop-Motions for Looms, of which the following description, in connection with the accompanying drawings, is a specification, like letters on the drawings representing like parts.

This invention relates to that class of looms wherein the stopping mechanism of the loom is operated through the intervention of stop-motion-actuating detectors upon failure or undue slackness of the warp-thread. The detectors are supported or hung upon the warp-threads and rise and fall with the latter in the formation of the shed, a guide being provided to prevent displacement of the detectors during such movement and also to act as a fixed fulcrum on which an abnormally-positioned detector is moved by or through engagement with a reciprocating feeler, such positioning of the detector being due to failure or undue slackness of its warp-thread.

The stopping mechanism for the loom is controlled as to its operation by the feeler-induced movement of the detector.

When the loom is running properly, the detectors are held by their warp-threads from engagement with the feeler.

In my present invention the detectors are shown as entirely independent of the shed-forming mechanism, and inasmuch as it is impracticable to release the usual shipper-lever by direct engagement therewith of a detector an intermediate device is provided, which, as herein shown, is operated by the lay upon the abnormal positioning and subsequent feeler-induced movement of a detector.

Figure 1, in vertical longitudinal section, represents a sufficient portion of a loom to be understood with one embodiment of my invention applied thereto. Fig. 2 is a perspective detail of a portion of the mechanism shown in Fig. 1, and Fig. 3 is a partial sectional detail view of a modified form of reciprocating means for the feeler.

The loom-frame A, the breast-beam A^X, lay A³, shipper-lever S, and the heddle-frames H H' may be and are of any usual or well-known construction. The lay is herein shown as pro-

vided at its rear side with a bunter a, adapted at times to engage a dog b, pivotally mounted at b' on a link b², jointed at b³ to a rocker-arm b⁴, mounted to rock on a suitable fulcrum-stud b⁵, the hub of the rocker-arm having a suitable knock-off arm b⁶ to throw the shipper-lever out of its holding-notch when the link b² is moved in the direction of arrow 10 by engagement of the dog b and bunter a. 60 The upper end of the link b² is supported by the fulcrum-stud b', which is extended into a slot c' of a guide-plate c, the hub of which is secured, as by a set-screw c², rigidly to a stud c^X, extended from the inner face of the loom 65 side, and said stud has also loosely mounted thereon a second hub b, provided with an upturned arm or finger d', extended beneath the dog b, and with a second depending arm d², to which is secured a light rod or shaft d^X, 70 extended across the loom back of the harness mechanism, as herein shown, and having at its other end a second arm b², (see Fig. 2,) journaled in the opposite loom side in any suitable manner.

The warp-stop-motion-actuating detectors, herein shown as a series of drop-wires, are preferably made as thin flat metallic plates f, preferably hooked, as at f', to embrace the warp-threads w and having longitudinal 80 slots f² therein, through which slots is extended across the loom a fixed bar f^X, forming a guide to prevent displacement of the detectors in the direction of the length of the warps, the said guide being assisted in this 85 function by an auxiliary bar f³, extended across the backs of the detectors and the rod d^X, which extends across their front. Obviously under normal conditions the detectors will rise and fall as the shed is formed, 90 and there will be no change in the position of the dog b from its full-line position, Fig. 1.

Below the lower ends of the detectors a feeler is mounted, said feeler being shown in Fig. 1 as a triangular bar m, rotatably mounted on a shaft k^X, held in suitable supports on the loom-frame and rotated in any suitable manner, as by a pinion m' in mesh with a rack m², connected by a link m³ with the lay, and to be moved back and forth thereby to turn 100 the feeler first in one direction and then in the other.

Referring to Fig. 1, it will be seen that when the loom is running properly the detectors supported by the warps, as w' , in the lower plane of the shed will be held thereby above or out of range of the longitudinal edges of the feeler; but if a warp-thread breaks, whether in the upper or the lower plane of the shed, or unduly slackens, the detector will drop and its lower end will be brought into position to be engaged by one of the edges of the feeler, and the detector will be swung thereby out of the vertical and on the guide-bar f^x as a fulcrum. Such a condition is shown in dotted lines, Fig. 1, and such feeler-induced movement of a detector will act upon the transverse bar d^x , pushing the same forward and thereby elevating the finger or arm d' to lift the dog b into position to be engaged by the bunter as the lay moves back. The completion of the backward stroke of the lay will move the link b^2 in the direction of the arrow 10 and by the means described will release the shipper-lever from its notch in the usual holding-plate to thereby stop the loom.

I prefer to separate the detectors by means of thin washers w^x , mounted on the guide-rod f^x between each two detectors.

Instead of the rack-and-pin mechanism for actuating the feeler, as shown in Fig. 1, other suitable mechanism may be devised, and in Fig. 3 I have shown a fixed shaft k^x as provided with a collar k , to which is rigidly secured one end of a spring s^x , the other end being attached to an annular flange k' on a disk k^2 , rotatably mounted on the shaft k^x , said flange being connected by a suitable strap h^3 with the lay-sword, the feeler-shaft being connected with said disk in any suitable manner. As the lay goes forward, the spring will be wound up and the rotation of the disk k^2 will act to rotate the feeler-shaft in one direction, and as the lay swings back the unwinding of the spring will act to rotate the disk, and consequently the feeler-shaft, in the reverse direction.

The mechanism herein shown is very simple, requiring little adjustment, and is rapid and effective in its operation.

50 The detector is subjected to very little strain when abnormally positioned, because the work to be performed at such time by the detector is merely that of lifting the dog into operative position to be engaged by the bunter.

Having fully described my invention, what I claim, and desire to secure by Letters Patent, is—

1. In a warp stop-motion for looms, longitudinally-slotted stop-motion-actuating detectors positioned abnormally by failure or undue slackness of the warp-threads, said detectors being applied to the latter, a fixed guide extended through the slots of and relatively to which the detectors are movable, a stationary bar extended back of the rear edges of the detectors, a feeler to engage and move

an abnormally-positioned detector on the guide, and stopping means for the loom, including a swinging bar extended across the front edges of the detectors, operated by feeler-induced movement of a detector, the fixed and swinging bars assisting the guide to prevent displacement of the detectors when the loom is running properly.

2. In a warp stop-motion for looms, stop-motion-actuating detectors positioned abnormally by failure or undue slackness of the warp-threads, said detectors being suspended by the latter and having each a longitudinal slot, a fixed guide-bar extended through the slots of the detectors, and acting to limit the detecting movement of a detector, a feeler to engage and swing an abnormally-positioned detector on said guide as a fulcrum, and stopping means for the loom, including a dog, and a controlling device therefor operated by the detector when swung by the feeler, to move the dog into operative position.

3. In a warp stop-motion for looms, stop-motion-actuating detectors vertically movable by the warp-threads when the loom is running properly, a guide for said detectors, a feeler to engage and move an abnormally-positioned detector, stopping mechanism for the loom, including a normally inoperative dog, a bunter, and a controlling device for the dog, operated by the feeler-induced movement of a detector.

4. In a warp stop-motion for looms, a series of stop-motion-actuating detectors normally supported by the warp-threads, a shipper, controlling means therefor, including a transverse bar to be engaged and swung by feeler-induced movement of an abnormally-positioned detector, a finger movable with said bar, and a dog controlled as to its position by said finger, and a feeler to engage and effect movement of a detector in abnormal position due to breakage or undue slackening of its warp-thread.

5. In a warp stop-motion for looms, a series of stop-motion-actuating detectors normally supported by the warp-threads, and a feeler adapted to engage and move an abnormally-positioned detector, combined with the lay, a bunter movable therewith, a shipper, controlling means therefor, including a dog, and a finger operated by the feeler-induced movement of a detector, to move the dog into position to be engaged by the bunter upon breakage on undue slackening of a warp-thread.

6. In a loom, the lay, a bunter movable therewith, a shipper, controlling means therefor, including a normally inoperative dog, a finger to position the dog, and a transverse actuating-rod connected with the finger, combined with a series of stop-motion-actuating detectors moved into abnormal position by breakage or slackening of a warp-thread and arranged adjacent said actuating-rod, and a feeler to engage an abnormally-positioned detector and move it, to effect the operation of the actuating-rod.

7. In a warp stop-motion for looms, a series of actuating-detectors hung on the warp-threads and longitudinally slotted, a fixed guide and fulcrum extended through the detector-slots, said guide limiting the abnormal movement of a detector, a feeler to engage and rock upon the guide an abnormally-positioned detector, and stopping means for the loom, including an actuating-rod adjacent the detectors and operated by the feeler-induced

movement of a detector, the guide being located between the actuating-rod and the feeler.

In testimony whereof I have signed my name to this specification in the presence of 15 two subscribing witnesses.

WILLIAM E. ALLEN.
